Primary Examiner — Susan E Krakower*Assistant Examiner* — Andrew Kerr(74) *Attorney, Agent, or Firm* — Jonathan Grant; Grant Patent Sevices(57) **CLAIM**

I claim the ornamental design for a spigot, as shown and described.

DESCRIPTION

FIG. 1 is a perspective view of a spigot, showing my new design;

FIG. 2 is a first side view thereof;

FIG. 3 is a second side view thereof;

FIG. 4 is a rear view thereof;

FIG. 5 is a front view thereof;

FIG. 6 is a top view thereof; and,

FIG. 7 is a bottom view thereof.

The broken lines in the drawing views represent environmental structure and form no part of the claimed design.
